UNITED STATES PATENT OFFICE.

DANIEL E. MIESS AND ALVYN R. MIESS, OF GLENDALE, CALIFORNIA.

LIQUID-FUEL BURNER.

1,282,907.

Specification of Letters Patent. Patented Oct. 29, 1918.

Application filed April 8, 1918. Serial No. 227,346.

To all whom it may concern:

Be it known that we, DANIEL E. MIESS and ALVYN R. MIESS, citizens of the United States, both residing at Glendale, in the county of Los Angeles, State of California, have invented new and useful Improvements in Liquid-Fuel Burners, of which the following is a specification.

This invention relates to burners for liquid fuel, such as petroleum distillates and the like. It is an object of this invention to provide a burner which may have an effective means of initial generation and at the same time act efficiently as a self-generator after being once initially started. Difficulty has been found in providing an efficient, simple and reliable initial generating means for such a burner as is herein described; and this difficulty has been overcome by our invention which involves a new organization of parts, producing a new burner combination with several features of novelty. The various novel features, the various objects of the invention, and the manner in which these objects are obtained, will be best understood from the following description of a preferred specific form of burner which embodies our invention.

For the purpose of this detailed description reference is had to the accompanying drawings in which—

Figure 1 is a vertical section of our improved burner;

Fig. 2 is a horizontal section on line 2—2 of Fig. 1;

Fig. 3 is a horizontal section on line 3—3 of Fig. 1;

Fig. 4 is a detail section on line 4—4 of Fig. 1; and

Fig. 5 is an enlarged detail section on line 5 of Fig. 1.

In most burners of the general class and character of the burner herein described the injection of the fuel gas or vapor into the mixing or combustion chambers is in an upward direction. One of the features of our burner is the reversal of this arrangement, causing the vapors to be injected downwardly into the mixing chambers. And from this feature there flow several very desirable results. In the drawings we show a burner in which the fuel nozzle 10 projects the vapors downwardly into the air

chamber (or suction chamber) 11 and into the mixing tube 12 which extends downwardly and discharges at its lower end into a mixing chamber 13 from whence the mixed vapors and air pass under a downwardly depending baffle wall 14 into a thin annular space 15 and thence through the perforated annular burner plate 16 to be burned in an annular flame surrounding the annular burner plate. The flame around the burner, with the heated gases of combustion rising from the flame, keep the nozzle at just the suitable temperature for completely vaporizing the fuel flowing through the retort 17 and flowing through the nozzle; but the heat is not sufficient to break down the fuel and cause its permanent gasification and deposit of carbon. It is an object of this invention to provide a construction in which a uniform heat is applied to the parts in which the fuel is vaporized sufficient to cause perfect vaporization of the fuel but never of so high a temperature as to cause decomposition to any substantial extent.

It is also an object of this invention to provide a means for heating the fuel right to its point of discharge through the vapor nozzle. In previous burners of this general class it has been very difficult to heat the fuel to its point of discharge; because usually this discharge has been located centrally under the burner where very little heat can reach it and where the cool incoming air usually passes directly over it and cools it to such an extent as to sometimes recondense the vapors to liquid form. This cooling of the vapors renders it necessary to overheat them in the retort where they are vaporized, resulting at times in their permanent gasification and deposit of carbon and consequent clogging of the retort.

Our specific preferred form of burner now embodies a substantially cup-shaped annular burner base 20 having at its outer upper edge a small flange 21 inside which the perforate annular burner plate, or screen, 16 rests. This plate or screen is removable by removing the head 25 which holds it in place on base 20. Within the annular burner plate the base has an upwardly projecting baffle ring or flange 22 inside the lower edge of the depending baffle ring or flange 14; so that the mixed vapors and air must pass

upwardly over the edge of baffle 22 and then downwardly under the lower edge of baffle 14 in order to reach the annular space 15. Baffle 14 depends from a head 25 which fits 5 over the upper edge of burner plate 16. Head 25 carries the downwardly extending mixing tube 12 whose lower open end projects to a point in the cup-shaped base 20 somewhat above the bottom of that base, 10 allowing sufficient space between the end of the mixing tube and the bottom of the base 20 for escape of the vapors and air.

Above head 25 there is a cap 30 whose edge rests upon the head 25; the cap being 15 held to the head by a suitable screw 26. The cap forms an air chamber 11 over the head. Fuel nozzle 10 discharges into the upper central part of this chamber 11 and directly downwardly through the chamber 20 into mixing tube 12. Nozzle 10 is mounted in a member 31 removably fitted into a boss or sleeve 32 on cap 30. The various inter-engaging surfaces of the nozzle 10, member 31, cap 30, and head 25 are either machined 25 after the parts are cast, or the castings are made from accurately machined patterns, so that the nozzle 10 is always accurately centered over the mixing tube 12. This is an important feature because it adds very 30 greatly to the uniformity of mixture made in the burner. Retort tube 17 is screw-threaded transversely through member 31 and is capped at 33 on its outer end. And the tube is also brazed or otherwise sealed into the 35 member 31 to make a tight joint. There is an annular groove 34 forming a passage around the retort tube and the retort tube has an opening 35 on its upper side through which the vapors emerge from the retort 40 tube into passage 34, passing thence through passage 36 to the nozzle 10. This particular construction we find to be very efficacious in preventing clogging of nozzle 10. We find that any small solid particles or de- 45 posits which would otherwise clog the nozzle 10, or partially clog it, and either stop or impair the operation of the burner, will not pass upwardly out through the opening 35, but will remain in the end of retort tube 17. 50 The end of retort tube 17 may be easily cleaned by the removal of cap 33. The retort tube is filled (preferably from end to end) with a filling of some material suitable to cause the minute subdivision of the liquid 55 as it passes through the tube. We find that a filling of what is known as "picture wire" does very well. This wire is a braid of very fine wire; and we place say half a dozen or more of these braided wires in the tube, 60 filling the tube as tightly as possible. Liquid percolates through the interstices and is thus finely subdivided and most effectively uniformly exposed to the heat applied to the tube, and thus most effectively uniformly

vaporized. Liquid fuel is fed into the re- 65 tort at the end designated 38 under a suitable pressure.

The retort and nozzle are removable. Member 31 removably fits in boss 32, so that the retort and nozzle may be easily lifted 70 out at any time. The nozzle and retort are supported by this boss 32, the retort tube resting on the upper end of the boss.

Cap 30 has, preferably cast integrally therewith, a circular flange 40 on its upper 75 face which forms a small cup into which a small amount of the fuel liquid may be poured for purposes of initially heating the retort. Also under the retort tube 37 we hang a small trough 41 into which a small 80 quantity of liquid is poured for the same purpose. This trough performs not only the office of a liquid holder but also the office of a baffle or protector for the retort tube when the burner is in normal operation. 85 The cap and trough may each have an asbestos wicking 42 to absorb the oil and cause it to burn slowly and uniformly.

Air is supplied to air chamber 11 through a plurality of air tubes 45 which extend 90 from the base 20 to the head 25, extending through both the base and the head. These tubes may be of any suitable number so as to be of the proper aggregate capacity to handle a sufficient quantity of air. We preferably use four tubes of about proportionate size shown. The lower ends of these tubes are welded or brazed into the burner base 20 and the upper ends are provided with washers 46 and nuts 47, which form 100 airtight joints between the head 25 and the tubes, preventing leakage of air; and which also perform the office of holding the head 25 in place, thus holding the head, the annular burner plate 16, and the base 20 together. The tubes may be secured to base 20 in any manner that makes a tight joint. 105

Below the lower ends of air tubes 45 we provide a circular damper plate 48 supported upon a collar 49 set upon standard 110 tube 50. This damper plate is revoluble, being provided with extension 51 to which a wire or rod may be connected; and is provided with damper openings 52 which may be registered partially or completely with the openings through tubes 45. In normal operation of the burner this damper plate is arranged to allow free ingress of air to the tubes; but during the starting of the burner the damper plate is turned so as to choke off the air to about one-fourth its normal amount. 115

The supporting standard for the burner preferably comprises a hollow base 55 and a standard 50 which is preferably made of a 120 tube or pipe screwed into the burner base 20. The lower end of this hollow standard 50 is plugged at 56 with some kind of a porous

wicking, preferably as asbestos wicking. In operating the burner it sometimes occurs that fuel is initially admitted to the retort tube before that tube is hot enough to completely vaporize the fuel, and as a consequence a small amount of liquid fuel will sometimes drop down through the nozzle into the burner base. This small amount of liquid fuel would interfere with the proper and normal operation of the burner if it stood in the base. Standard tube 50 is of sufficient capacity to hold any such amount of liquid fuel; and the interior bottom surface of the base may be made so as to slope slightly toward the tube 50 so as to drain all of this liquid into the tube. The liquid having passed into the tube will slowly drain out through wicking 56 and into the base or ash pan of the stove or furnace in which the burner is installed. The wicking allows this liquid fuel to drain off and at the same time prevents any leakage of vapor out of the burner.

To start the burner a small amount of the liquid fuel (usually kerosene or a similar grade of petroleum distillate) is placed in the cup 40 and trough 41 and ignited. The asbestos or other wicking 42 absorbs the liquid fuel and prevents it burning too fast when ignited. When the retort tube and the nozzle members 31 have been sufficiently heated, then the liquid fuel is admitted by manipulation of a valve on the fuel line leading to the retort end 38; and this fuel is immediately vaporized and the vapor projected downwardly under pressure through air chamber 11 and tube 12 into the lower mixing chamber 13. If any of the fuel is at first not fully vaporized, it passes into standard tube 50 as explained. The air tubes 45 are at first partially closed, to allow only a limited quantity of air to pass into air (or suction) chamber 11, and this air is drawn down by the vapor jet through mixing tube 12 into mixing chamber 13, and thence along with the vapors over baffle 22 and under baffle 14 and out through burner plate 16 to be ignited and burned. During its passage through the various chambers, etc., the air and vapors are very thoroughly mixed; so that when they reach the burner plate they are mixed so intimately that perfect, or very nearly perfect, combustion may then take place. As soon as the burner is warmed up, the air openings are widened so as to allow ingress of the maximum or normal quantity of air. The flame then burns in a purplish blue color in an annular ring around the burner. The flame is maintained at a considerable distance from the burner plate, so that the burner plate is not directly exposed to the flame heat. The greatest temperature in the flame is of course in its middle or outer portions, in an annular ring around

the burner. But the products of combustion and the heated air rising from the burner maintain a heated zone around the nozzle and around the inner end of the retort tube at just the right temperature to thoroughly, uniformly and continuously vaporize the liquid fuel without overheating it. Trough 41 protects the outer part of the retort tube so that the outer parts receive just the requisite amount of heat to thoroughly and uniformly vaporize the fuel without overheating. Thus, from the time the fuel enters the retort tube until it is discharged from the nozzle, it is subjected to a substantially uniform temperature (or perhaps somewhat gradually increasing temperature toward the nozzle) to cause its vaporization and to maintain that vapor up to the point of actual discharge. The point of discharge at the nozzle is substantially as hot or hotter than any other place in the vaporizing passage. This uniform temperature is maintained and not substantially overreached even when the burner is operated continuously for long periods. Furthermore, if more fuel is admitted, in order to have a larger flame and deliver more heat, the arrangement is such that the additional heat delivered to the retort tube and to the nozzle parts is substantially just sufficient to offset the additional amount of fuel which must be vaporized, and cause vaporization without deposit of carbon. Of course, in the operation of the burner there may at times be some gasification of the fuel, so that both vapors and gases are made; and we do not limit ourselves to the exclusive use of vapors as distinguished from gases.

During the operation the whole burner becomes warm; and the air which enters through air tube 45 and passes through the various chambers and through mixing tube 12 and over and under the baffles, is warmed during its passage; as are also the vapors; so that the final thoroughly incorporated mixture of air and vapor is discharged through the burner plate is pre-heated and is thus in condition for efficient combustion.

Having described a preferred form of our invention, we claim:—

1. A liquid fuel burner comprising a burner body having an outer perforated burner plate and a mixing chamber, a vapor nozzle centrally above the mixing chamber and discharging downwardly thereinto, and a fuel vaporizing retort above and to one side of the burner body leading from one side of the burner body to and discharging into the nozzle.

2. A liquid fuel burner comprising a circular burner body having an annular perforated burner plate and having a mixing chamber inside the body, a vapor nozzle projecting vapor downwardly centrally from

above into the mixing chamber, and a fuel vaporizing retort above and to one side of the burner body and leading into and communicating with the nozzle from one side.

5 3. A liquid fuel burner comprising a circular burner body having an annular perforated burner plate and having a mixing chamber inside the body, a vapor nozzle projecting vapor downwardly centrally from above into the mixing chamber, a fuel vaporizing retort above and to one side of the burner body and leading into and communicating with the nozzle from one side, and means under the outer portions of the retort to protect it against the direct flame of the burner.

20 4. A liquid fuel burner comprising a circular burner body having an annular perforated burner plate and having a mixing chamber inside the body, a vapor nozzle projecting vapor downwardly centrally from above into the mixing chamber, a fuel vaporizing retort above and to one side of the burner body and leading into and communicating with the nozzle from one side, and means under the outer portions of the retort to protect it against the direct flame of the burner, said means comprising a trough suspended from the retort and adapted to hold a suitable quantity of liquid fuel to be ignited and burned for initially heating the retort.

25 5. In a burner of the character described, a body having a perforated burner plate and a mixing chamber, means for projecting a vaporous fuel downwardly into the mixing chamber, and means at the lower part of the mixing chamber for draining off any liquid fuel therein embodying a draining opening and a stopper of porous material adapted to allow passage of liquid but to prevent passage of gas or vapor.

30 6. In a burner of the character described, a body having a perforated burner plate and a mixing chamber, means for projecting a vaporous fuel downwardly into the mixing chamber, and means at the lower part of the mixing chamber for draining off any liquid fuel therein, said means embodying a well communicating at its upper end with the lower part of the chamber and having at its lower end a porous stopper adapted to allow liquid to slowly escape and adapted to prevent egress of vapors from the burner.

35 7. In a burner of the character described wherein a vaporous fuel is projected downwardly into the burner, a nozzle member having a vertical passage, a nozzle at the lower end of said passage, and a retort tube extending through said member and across said passage, the tube having an outlet opening at its upper side to allow vapors to pass upwardly out of the tube, and there being a passage leading around the tube from

the outlet opening to the passage in said member.

8. In a burner of the character described wherein a vaporous fuel is projected downwardly into the burner, a nozzle member having a vertical passage therein, a nozzle at the lower end of said chamber, and a retort tube extending across the upper end of the passage, the tube having an outlet opening at its upper side to allow vapors to pass upwardly out of the tube, and there being a passage leading around the tube from the outlet to the vertical passage, the tube projecting through and extending beyond the said nozzle member and provided with a removable cap on its end for cleaning purposes.

20 9. A burner of the character described, comprising a body having an upper air chamber into which vaporous fuel is discharged centrally downwardly, a mixing tube extending downwardly from said air chamber, the body having a lower mixing chamber into which the lower end of said mixing tube discharges, a perforated burner plate forming the outer wall of said mixing chamber, and means to supply air to the air chamber embodying tubes which extend vertically through the mixing chamber and discharge into the air chamber.

25 10. A burner of the character described, comprising a body having an upper air chamber into which vaporous fuel is discharged centrally downwardly, a mixing tube extending downwardly from said air chamber, the body having a lower mixing chamber into which the lower end of said mixing tube discharges, a perforated burner plate forming the outer wall of said mixing chamber, and means to supply air to the air chamber embodying tubes which extend vertically through the mixing chamber and discharge into the air chamber; said means for discharging a vaporous fuel downwardly into the air chamber embodying a downwardly projecting nozzle member centrally situated over the burner body, and a substantially horizontal retort tube connecting with and discharging into the nozzle member.

30 11. A burner of the character described, comprising a body having an upper air chamber into which vaporous fuel is discharged centrally downwardly, a mixing tube extending downwardly from said air chamber, the body having a lower mixing chamber into which the lower end of said mixing tube discharges, a perforated burner plate forming the outer wall of said mixing chamber, means to supply air to the air chamber embodying tubes which extend vertically through the mixing chamber and discharge into the air chamber; said means for discharging a vaporous fuel downwardly into the air chamber embodying a down-

- wardly projecting nozzle member centrally situated over the burner body, and a substantially horizontal retort tube connecting with and discharging into the nozzle member, a liquid fuel receiving cup on the burner body around the nozzle, and a protective baffle in the form of a trough adapted to receive liquid fuel for generative purposes under the retort tube.
12. A burner of the character described, comprising a body having an upper air chamber into which vaporous fuel is discharged centrally downwardly, a mixing tube extending downwardly from said air chamber, the body having a lower mixing chamber into which the lower end of said mixing tube discharges, a perforated burner plate forming the outer wall of said mixing chamber, and means to supply air to the air chamber embodying tubes which extend vertically through the mixing chamber around the mixing tube and discharge into the air chamber; said means for discharging a vaporous fuel downwardly into the air chamber embodying a downwardly projecting nozzle member centrally situated over the burner body, and a substantially horizontal retort tube connecting with and discharging into the nozzle member; and a protecting member suspended under the retort tube protected against direct flame.
13. A burner of the character described, comprising a burner body having a substantially cup-shaped burner base, an annular perforated burner plate mounted upon the outer edge of the burner base, a head mounted upon the upper edge of the burner plate; said head and base and burner plate forming a mixing chamber, said head carrying a downwardly depending mixing tube open at both ends and discharging into the parts of said mixing chamber, an upper cap mounted upon the head and inclosing an air chamber over the head, a downwardly projecting nozzle centrally mounted in the upper part of the cap and adapted to project vaporous fuel centrally downwardly through the air chamber and into and through the central mixing tube; and means to supply air to the air chamber.
14. A burner of the character described, comprising a burner body having a substantially cup-shaped burner base, an annular perforated burner plate mounted upon the outer edge of the burner base, a head mounted upon the upper edge of the burner plate, said head and base and burner plate forming a mixing chamber, said head carrying a downwardly depending mixing tube open at both ends and discharging into the lower part of said mixing chamber, an upper cap mounted upon the head and inclosing an air chamber over the head, a downwardly projecting nozzle centrally mounted in the upper part of the cap and adapted to project vaporous fuel centrally downwardly through the air chamber and into and through the central mixing tube; means to supply air to the air chamber, said means comprising a plurality of air tubes extending through the burner base and open at the lower ends to atmosphere and extending upwardly through the mixing chamber and through the head and discharging air into the air chamber; said head having a depending an-
- per part of the cap and adapted to project 65 vaporous fuel centrally downwardly through the air chamber and into and through the central mixing tube; and means to supply air to the air chamber, said means comprising a plurality of air tubes extending through 70 the burner base and open at the lower ends to atmosphere and extending upwardly through the lower mixing chamber and through the head and discharging air into the air chamber.
15. A burner of the character described, comprising a burner body having a substantially cup-shaped burner base, an annular perforated burner plate mounted upon the outer edge of the burner base, a head mounted upon the upper edge of the burner plate, said head and base and burner plate forming a mixing chamber, said head carrying a downwardly depending mixing tube open 75 at both ends and discharging into the lower parts of said mixing chamber, an upper cap mounted upon the head and inclosing an air chamber over the head, a downwardly projecting nozzle centrally mounted in the upper part of the cap and adapted to project 80 vaporous fuel centrally downwardly through the air chamber and into and through the central mixing tube; means to supply air to the air chamber; the interior surface of said burner base sloping somewhat toward the center, a liquid well communicating at its upper end with the center of the base and adapted to receive and temporarily hold any excess of liquid, and a porous plug for the lower end of said well 85 adapted to slowly pass any accumulated liquid, and adapted to prevent any egress of vapors from the burner.
16. A burner of the character described, comprising a burner body having a substantially cup-shaped burner base, an annular perforated burner plate mounted upon the outer edge of the burner base, a head mounted upon the upper edge of the burner plate, said head and base and burner plate forming a mixing chamber, said head carrying a downwardly depending mixing tube open at both ends and discharging into the lower part of said mixing chamber, an upper cap 90 mounted upon the head and inclosing an air chamber over the head, a downwardly projecting nozzle centrally mounted in the upper part of the cap and adapted to project 95 vaporous fuel centrally downwardly through the air chamber and into and through the central mixing tube; means to supply air to the air chamber, said means comprising a plurality of air tubes extending through the burner base and open at the lower ends to atmosphere and extending upwardly 100 through the mixing chamber and through the head and discharging air into the air chamber.
17. A burner of the character described, comprising a burner body having a substantially cup-shaped burner base, an annular perforated burner plate mounted upon the outer edge of the burner base, a head mounted upon the upper edge of the burner plate, said head and base and burner plate forming a mixing chamber, said head carrying a downwardly depending mixing tube open at both ends and discharging into the lower part of said mixing chamber, an upper cap 105 mounted upon the head and inclosing an air chamber over the head, a downwardly projecting nozzle centrally mounted in the upper part of the cap and adapted to project vaporous fuel centrally downwardly through the air chamber and into and through the central mixing tube; means to supply air to the air chamber, said means comprising a plurality of air tubes extending through the burner base and open at the lower ends to atmosphere and extending upwardly 110 through the mixing chamber and through the head and discharging air into the air chamber.
18. A burner of the character described, comprising a burner body having a substantially cup-shaped burner base, an annular perforated burner plate mounted upon the outer edge of the burner base, a head mounted upon the upper edge of the burner plate, said head and base and burner plate forming a mixing chamber, said head carrying a downwardly depending mixing tube open at both ends and discharging into the lower part of said mixing chamber, an upper cap 115 mounted upon the head and inclosing an air chamber over the head, a downwardly projecting nozzle centrally mounted in the upper part of the cap and adapted to project vaporous fuel centrally downwardly through the air chamber and into and through the central mixing tube; means to supply air to the air chamber, said means comprising a plurality of air tubes extending through the burner base and open at the lower ends to atmosphere and extending upwardly 120 through the mixing chamber and through the head and discharging air into the air chamber.
19. A burner of the character described, comprising a burner body having a substantially cup-shaped burner base, an annular perforated burner plate mounted upon the outer edge of the burner base, a head mounted upon the upper edge of the burner plate, said head and base and burner plate forming a mixing chamber, said head carrying a downwardly depending mixing tube open at both ends and discharging into the lower part of said mixing chamber, an upper cap 125 mounted upon the head and inclosing an air chamber over the head, a downwardly projecting nozzle centrally mounted in the upper part of the cap and adapted to project vaporous fuel centrally downwardly through the air chamber and into and through the central mixing tube; means to supply air to the air chamber, said means comprising a plurality of air tubes extending through the burner base and open at the lower ends to atmosphere and extending upwardly through the mixing chamber and through the head and discharging air into the air chamber; said head having a depending an-

- 5 nular baffle flange close to the annular burner plate to form a thin annular space between the flange and plate, and under which baffle the vapors and air must pass in order to
10 reach the burner plate, and said burner base having an upwardly projecting baffle flange inside the lower edge of the depending baffle flange and over which last mentioned baffle flange the vapors and air must pass.
- 15 17. A burner of the character described, comprising a burner body having a substantially cup-shaped burner base, an annular perforated burner plate mounted upon the outer edge of the burner base, a head mounted upon the upper edge of the burner plate, said head and base and burner plate forming a mixing chamber, said head carrying a downwardly depending mixing tube open at both ends and discharging into the lower
20 part of said mixing chamber, an upper cap mounted upon the head and inclosing an air chamber over the head, a downwardly projecting nozzle centrally mounted in the upper part of the cap and adapted to project vaporous fuel centrally downwardly through the air chamber and into and through the central mixing tube; a horizontal retort tube connected at its inner end with the nozzle and extending outwardly, a liquid receiving
25 cup on the top of the burner cap, a protective baffle and liquid receiving trough under the retort tube; means to supply air to the air chamber, said means comprising a plurality of air tubes extending through the burner base and open at the lower ends to atmosphere and extending upwardly through the mixing chamber and through the head and discharging air into the upper mixing chamber; said head having a depending an-
30 nular baffle flange close to the annular burner plate to form a thin annular space between the flange and plate, and under which baffle flange the vapors and air must pass in order to reach the burner plate, and said burner
35 base having an upwardly projecting baffle flange inside the lower edge of the depending baffle flange and over which last mentioned baffle flange the vapors and air must pass.
- 40 18. A liquid fuel burner comprising a circular burner body having an annular perforated burner plate and having a mixing chamber inside the body, a vapor nozzle projecting vapor downwardly from above
45 into the mixing chamber, a fuel vaporizing retort above the burner body and communicating with the nozzle, and a liquid fuel cup upon the upper part of the burner surrounding the fuel nozzle and adapted to hold a small quantity of liquid fuel for initial generation purposes.
- 50 19. A liquid fuel burner comprising a circular burner body having an annular perforated burner plate and having a mixing

chamber inside the body, a vapor nozzle 65 projecting vapor downwardly from above into the mixing chamber, a fuel vaporizing retort above the burner body and communicating with the nozzle, a liquid fuel cup upon the upper part of the burner surrounding the fuel nozzle and adapted to hold a small quantity of liquid fuel for initial generation, and a protective baffle and liquid fuel receiving trough under the retort tube.

70 20. A burner of the character described, comprising a body having an upper air chamber into which vaporous fuel is discharged centrally downwardly, a mixing tube extending downwardly from said air chamber, the body having a lower mixing chamber into which the lower end of said mixing tube discharges, a perforated burner plate forming the outer wall of said mixing chamber, and means to supply air to the air chamber embodying tubes which extend 80 vertically through the mixing chamber and discharge into the air chamber, the lower ends of the tubes being open at the bottom of the burner, and an air control damper mounted on the lower side of the burner and 90 adapted to control the tube openings.

95 21. A burner of the character described, comprising a burner body having a substantially cup-shaped burner base, an annular perforated burner plate mounted upon the outer edge of the burner base, a head mounted upon the upper edge of the burner plate, said head and base and burner plate forming a mixing chamber, said head carrying a downwardly depending mixing tube open at both ends and discharging into the lower part of said mixing chamber, an upper cap mounted upon the head and inclosing an air chamber over the head, a downwardly projecting nozzle centrally mounted in the upper part of the cap and adapted to project vaporous fuel centrally downwardly through the air chamber and into and through the central mixing tube; and means to supply air to the air chamber, said means comprising a plurality of air tubes extending through the burner base and open at the ends to atmosphere and extending upwardly through the lower mixing chamber and through the head and discharging air into the air chamber, said tubes being affixed to both the base and head to hold the burner parts together.

100 22. In a burner of the class described, a burner base and a burner head and a plate between them forming a chamber, a cap over 105 the head forming another chamber, and air tubes extending through the base and head and affixed thereto to hold the burner parts together.

110 23. A burner of the character described, comprising a body having an air chamber at one end into and through which vaporous fuel is projected substantially centrally, a

mixing tube extending from the air chamber, the body having a mixing chamber into which the mixing tube discharges, a perforated burner plate forming the outer wall 5 of the mixing chamber, and air tubes extending through the mixing chamber and discharging into the air chamber to supply air to that chamber.

In witness that we claim the foregoing we have hereunto subscribed our names this 3d 10 day of April, 1918.
